UNITED STATES PATENT OFFICE.

ARTHUR A. SHAFFER, OF ERIE, PENNSYLVANIA, ASSIGNOR TO RICKERT-SHAFFER COMPANY, OF ERIE, PENNSYLVANIA, A CORPORATION OF PENNSYLVANIA.

THREADING-DIE MECHANISM.

1,345,709.

Specification of Letters Patent.

Patented July 6, 1920.

Application filed November 14, 1918. Serial No. 262,544.

To all whom it may concern:

Be it known that I, ARTHUR A. SHAFFER, a citizen of the United States, residing at Erie, in the county of Erie and State of Pennsylvania, have invented certain new and useful Improvements in Threading-Die Mechanism; and I do hereby declare the following to be a full, clear, and exact description of the invention, such as will enable others skilled in the art to which it pertains to make and use the same, reference being had to the accompanying drawings, and to the letters of reference marked thereon, forming part of this specification.

15 My invention relates to threading die mechanism, and particularly to rotatable dies having means for tapering the thread being cut therewith, and automatically opening and closing the die at predetermined 20 points in its traverse.

The object of my invention is to provide a rotatable threading die with means whereby the die will be either gradually opened as it moves on to the work, so that the thread 25 cut thereby will be somewhat tapered, or according to its adjustment the thread will be cut straight, and to provide mechanism coöperating with the die whereby when the thread is completed the die will be instantly 30 opened, moved back off of the work and closed ready to cut another thread.

The features of my invention are herein-after fully set forth and described and illustrated in the accompanying drawings in 35 which:—

Figure 1, is a front end view of a threading die embodying features of my invention.

Fig. 2, is a side view in elevation of the 40 same.

Fig. 3, is an opposite side view in elevation of the same.

Fig. 4, is a transverse section of the same on the line $x-x$ in Fig. 3.

45 Fig. 5, is a side view in elevation of a section of a machine and mechanism operating the die.

Fig. 6, is a vertical section of the same on the line $y-y$ in Fig. 5.

50 In these drawings A represents the die holder, supporting the dies a mounted there-

in; B the driving stem thereon; C the rotatable cam-sleeve on the body, operating the dies in the usual manner; and D the plate ring secured to the end of the die-holder 55 A, securing the cam-sleeve in place thereon, all of which parts are of the usual construction and operation.

Mounted upon the cam-sleeve C there is a ring E adapted to slide back and forth on the cam-sleeve C, and secured to this ring E there are tubular guide rods F which extend back through the annular extension A' of the die-holder A, and *inter alia* causes the ring E to rotate in unison with the die-holder A. These hollow guide rods F are provided with internal spiral springs F' (see Fig. 2) which operate normally to force the ring E forward toward the outer end of the cam-sleeve C, to the point illustrated in 65 Figs. 2, 3 and 4.

On the outer surface of the cam-sleeve C, I secure a longitudinal guide G which extends through an annular recess e in the inside face of the ring E and preferably has 75 one edge g thereof inclined to the axis of the cam-sleeve C; and on the inside face of the ring E there is secured a movable plate H, one end of which contacts with the edge g of the guide G and operates as the 80 ring E is moved back toward the extension A' of the die-holder A, to gradually rotate the cam-sleeve C to slightly open the dies a and when the cut on the work is completed the ring passes off of the rear end of the 85 guide G and permits the cam-sleeve C to rotate and open the dies.

The movable plate H is adjustable on the ring E which is provided with a scale e' for determining the amount of such adjustment. Mounted in the extension A' of the die-holder A (see Figs. 3 and 4) there is a segment of bevel gear I which engages a segment of gear-teeth e on the cam-sleeve C 95 and operates to rotate the cam-sleeve C to close the dies a when the rearward traverse of the die is completed. For operating the gear segment I there is a lever I' on the stem thereof adapted to be operated as hereinafter set forth.

In operating the threading-die mechanism and coöperating therewith the thread-

ing die is preferably mounted in the machine-stock or head J of an automatic screw machine provided with the usual gearing (not shown) for rotating the dies and other tools mounted in such head, and on the upper part of the machine frame K (see Figs. 5 and 6) I mount a lever L L', the part L thereof being in the form of a yoke provided on the end of each arm thereof with 5 rollers l adapted to engage the face of the ring E on the die and force it back on the cam-sleeve C thereof as the die moves on to the work M, and during said movement cause the end h of the plate H on said ring to 10 travel back on the inclined surface g of the guide G on the cam-sleeve C, to slightly rotate, and thereby gradually open the dies a during the process of cutting the thread m on the work M, until the ring E passes off 15 of the rear end of the guide G which allows the cam-sleeve C to rotate and open the die. When the ring E on the die-holder engages the roller l on the bifurcated lever L, the lever L gives way until said lever reaches 20 the limit of its movement, when the rollers l force the ring E backward on the die holder, and when the die-holder recedes from the work, M, the spring-pressed plunger engaging the lever L' causes the bifurcated levers L L' to swing clear from the work M as shown in Fig. 5, so that access thereto may be had.

For closing the die for again moving it on to the work, I mount on the part K', of the 25 machine frame a centrally pivoted lever N N'; the upper arm N of this lever extends upward opposite the central line of the part A' of the die-holder A where it is provided with an inwardly extending lug or boss n adapted to be brought into engagement with the arm I' on the segmental gear I and rotate it, and thereby operate the cam-sleeve C to close the dies a ready for a new operation. This lever L L' is actuated by having 30 a roller n' mounted on the lower end of said arm, contact with the surface of a rotating drum O mounted in the machine frame, which drum is provided with an inclined projection o which, as the drum O rotates, 35 is at the proper time brought into contact with the roller n', which operates to move the boss n on the arm N of the lever, inwardly so as to engage the arm I' as the die-holder is rotated.

50 The drum O is also provided with a cam-groove P which is engaged by a roller p on the lower part of the machine stock or head support J', and operates as the drum O is rotated to move the head or stock J forward toward the work and backward therefrom in the usual manner.

From the foregoing description of the mechanism and its operation it is believed that further description of the operation of 55 the mechanism is unnecessary.

Therefore what I claim as new and desire to secure by Letters-Patent is:

1. In a device of the character described, a die-holder, dies mounted therein, a rotatable cam sleeve on said die-holder for actuating said dies, an inclined plate secured 70 thereon, a longitudinally movable ring engaging said inclined plate to rotate said cam ring, and means to prevent the rotation of said ring on the die-holder, substantially as 75 set forth.

2. In a device of the character described, a die-holder, dies mounted therein, a rotatable cam sleeve on said die-holder for actuating said dies, an inclined plate secured 80 thereon, a longitudinally movable ring engaging said inclined plate to rotate said cam ring, and spring actuated guide rods secured to said ring and slidably mounted in the die holder to prevent rotation of said 85 ring on said die holder, substantially as set forth.

3. In a device of the character described, a rotatable die holder, dies mounted therein, a cam-sleeve rotatable upon the die holder 90 for actuating said dies, miter gear teeth thereon, a circumferential shoulder on said die holder, a shaft radially mounted on said shoulder, a miter gear wheel secured on said shaft and intermeshing with the gear teeth 95 on said cam ring, and a lever secured on said shaft to operate said shaft and gear wheel to rotate said cam ring, substantially as set forth.

4. In a device of the character described, 100 a self opening and closing rotatable threading-die comprising substantially a die-holder, dies mounted therein, a cam-sleeve rotatable on the die-holder, a ring movable longitudinally over the cam-sleeve, a guide-plate thereon engaging said ring, spring actuated guide rods on said ring sliding through an extension on the die-holder and a yoke lever on the machine frame engaging the front face of said ring as the threading 110 die moves upon the work and moving the ring backward over the cam-sleeve, substantially as set forth.

5. In a device of the character described, 115 a rotatable threading-die comprising substantially a die-holder, threading dies mounted therein, a cam-sleeve rotatable upon the die-holder for actuating the threading dies, a segment of gear on said cam-sleeve, a segment of gear-wheel mounted 120 in the die-holder and intermeshing with the gear on the cam-sleeve, an arm on said gear wheel for rotating it, and means on the machine frame for intermittently engaging said arm and rotating it, substantially as 125 set forth.

6. In a device of the character described, 130 a rotatable threading-die mechanism comprising substantially a die-holder, threading dies mounted therein, a cam-sleeve rotatable

upon the die-holder for opening and closing the threading dies, a segment of gear on the cam-sleeve, a segmental gear-wheel mounted in the die-holder and intermeshing 5 with the gear teeth on the cam-sleeve, an arm on said gear wheel for rotating it, an oscillating lever pivoted on the machine

frame and movable into engagement with said gear-wheel arm, and a cam-drum engaging said lever and intermittently operating 10 it, substantially as set forth.

In testimony whereof I affix my signature.

ARTHUR A. SHAFFER.
